NEHEMIAH HAWKINS, OF CHICAGO, ILLINOIS.

Letters Patent No. 85,930, dated January 19, 1869.

IMPROVEMENT IN CONSTRUCTION OF ELEVATOR-BUCKETS.

The Schedule referred to in these Letters Patent and making part of the same

To all whom it may concern:

Be it known that I, NEHEMIAH HAWKINS, of Chicago, in the county of Cook, and State of Illinois, have invented an Improvement in Elevator-Buckets; and I do hereby declare that the following is a full, clear, and exact description of the same, reference being had to the accompanying drawings, and letters marked thereon, making a part of this description, in which—

Figure 1 is a perspective representation of my improved elevator-bucket.

Figure 2, a perspective view of one of the ends of the bucket.

Figure 3, a transverse central section.

The nature of the present invention consists in so improving the cast and plate-metal elevator-bucket as to provide shoulders for the nosing-plates of the front edge to rest upon, and thus prevent them from being detached as soon as the rivets with which they are fastened become worn, and in riveting the body of the bucket to flanges, or projecting lugs, on the ends of the bucket.

To enable others to fully comprehend the construction of my invention, I have marked corresponding parts with like letters, and will now give a detailed description.

A represent the ends of the bucket, which, if they are cast-iron, have flanges, B B', cast solid with them, but if made of plate-metal, have the flanges formed by means of suitable dies for this purpose, holes, C, being made through the flanges, to receive the rivets with which the body, D, is fastened to the ends.

This body is made of sheet-metal, or other suitable material, and at its upper and front edge it is strengthened by means of metal plates E F, figs. 1 and 3, which are placed on the opposite sides of the body, D, and clamped firmly to it, by means of rivets, G, the end-rivets passing through the flanges B', and the plate F, fitting into recesses, S, in the ends A, hold the plates, body, and ends firmly together.

These plates E F are not claimed to be new, but the manner of so securing them to the body D, and flanges B' of the ends A, as to bind all of these parts firmly together, constitutes a novel feature, not shown in any bucket of which I have knowledge.

This novelty is made more apparent in view of the recesses S, which permit the front side of the plate F to be placed wholly inside of the body D, and to rest on shoulders at the lower parts of the said recesses, thus providing a continuous bearing for the front of the body, without bending it, as would be the case if the plate F projected wholly outside of the flanges B'.

The construction of the ends A is very different from that shown in the patent for elevator-buckets granted to J. S. Brooks, November 24, 1863, inasmuch as he uses two flanges on each end, and clamps the body between them by means of a bolt passing through the ends, and fastening with a nut.

Further, ends made with double flanges, with grooves between them, (like those which Brooks shows,) are much heavier than those made by me, and the bolt, as a fastening, is very objectionable, inasmuch as it prevents the bucket from properly filling with grain, and as the nut with which it is fastened soon cuts through the side of the spout.

My invention is made with especial reference to obviating these difficulties, and I consequently use single flanges, made as light as possible and yet support the body, and, as an additional security, fasten the ends of the plates E F, body D, and flanges B', with the same rivets, as shown at G, fig. 1.

I do not claim to have made wholly a new bucket, but have been thus particular in this description in order to show clearly one which is made complete with my improvement.

Having thus described my invention,

What I claim, and desire to secure by Letters Patent of the United States, is—

An elevator-bucket, the ends A of which have flanges B B' riveted to the body D, and have recesses S formed in their front edges, to receive and support the nose-plates E F, said plates being also riveted to the flanges, substantially as and for the purpose herein set forth.

Done, November 25, A. D. 1868.

NEHEMIAH HAWKINS.
